United States Patent Office

Des. 199,948
Patented Dec. 29, 1964

199,948

COMB

Carl F. Hilldring, Butler, N.J., assignor to Amerace Corporation, New York, N.Y., a corporation of Delaware

Filed Sept. 6, 1963, Ser. No. 76,502

Term of patent 7 years

(Cl. D86—8)

Fig. 1.

Fig. 2.

Fig. 3.

FIG. 1 is a side elevational view of a comb showing my new design.

FIG. 2 is a front view, looking toward the open end of the teeth of the comb; and

FIG. 3 is a cross-sectional view, taken along the line 3-3 of FIG. 1.

I claim:

The ornamental design for a comb, substantially as shown.
